(57) CLAIM

I claim, the ornamental design for a shoe, as shown and described.

DESCRIPTION

FIG. 1 is a front perspective view of a shoe, showing my new design;

FIG. 2 is a rear perspective view thereof;

FIG. 3 is a front elevation view thereof;

FIG. 4 is rear elevation view thereof;

FIG. 5 is a right elevation view thereof taken from the right of FIG. 3;

FIG. 6 is a left elevation view thereof taken from the left of FIG. 3; and

FIG. 7 is a top plan view thereof; and,

FIG. 8 is a bottom plan view thereof.

The broken lines represent the portions of the design that form no part of the claim.

UNITED STATES PATENT AND TRADEMARK OFFICE
CERTIFICATE OF CORRECTION

PATENT NO. : Des. 587,883 S
APPLICATION NO. : 29/303497
DATED : March 10, 2009
INVENTOR(S) : Frederic Beauger

It is certified that error appears in the above-identified patent and that said Letters Patent is hereby corrected as shown below:

Title page item [30] should read priority to European Community Design No. 000772223-0002 filed August 10, 2007. Currently the Patent indicates an erroneous Foreign Application Priority date of October 8, 2007.

Signed and Sealed this

Twenty-fifth Day of August, 2009

David J. Kappos
Director of the United States Patent and Trademark Office
